UNITED STATES PATENT OFFICE.

TALBERT GRANT WEAVER, OF LINCOLN, ARKANSAS.

NON-SINKABLE VESSEL.

1,243,646.

Specification of Letters Patent. Patented Oct. 16, 1917.

Application filed May 12, 1917. Serial No. 168,190.

To all whom it may concern:

Be it known that I, TALBERT G. WEAVER, a citizen of the United States, residing at Lincoln, in the county of Washington and 5 State of Arkansas, have invented certain new and useful Improvements in Non-Sinkable Vessels, of which the following is a specification, reference being had to the accompanying drawings.

10 This invention relates to ships, and more particularly to the hull construction therefor.

15 The general object of the invention is to so construct the hull of a vessel that the vessel will be practically unsinkable and a further object is to so construct the hull of the vessel that torpedoes, mines and like engines of destruction can do but relatively small damage to the vessel.

20 A further object is to so construct the hull of the vessel that it consists of conjoined cells or compartments of relatively large size, each cell or compartment being filled 25 with compressed cotton, the cotton being held under compression by intermediate steel plates and bolts.

Other objects will appear in the course of the following description.

My invention is illustrated in the accompanying drawings, wherein:—

30 Figure 1 is a transverse sectional view of a vessel constructed in accordance with my invention;

35 Fig. 2 is a horizontal sectional view relatively enlarged of one of the compartments;

Fig. 3 is a vertical sectional view through one of the compartments and showing one of the side walls.

40 Referring to these drawings, it will be seen that I form the hull of the vessel with a plurality of compartments, each about ten feet square and ten feet deep. The outside wall 10 of the hull may be constructed of wood, steel plate, or of any other suitable 45 material and constructed in any usual or suitable manner. Within this outer wall 10 is formed a plurality of compartments 11 and 11^a. These compartments may be of uniform size, of different sizes depending 50 upon the locality of the compartment and, of course, the size will vary with the size of the vessel. Thus in Fig. 1, I have shown the

sides of the vessel as being provided with compartments 11^a, which are 10 feet square and which extend upward from the bottom 55 of the hull to a point above the water line and I have shown the bottom of the vessel as formed with a series of compartments 11, which are 10 feet square and 10 feet deep. Preferably each of these compartments will 60 be 10 feet square and where possible 10 feet deep more or less, except at the sides, where the compartments may run the full height of the vessel more or less. The walls of the compartments will be formed preferably of 65 steel plates 12 securely riveted, bolted or otherwise attached to the outer wall 10 and in each compartment there is to be disposed a plurality of layers of compressed cotton designated 13 and a plurality of intermediate plates 14. For instance, in a compartment which is ten feet deep, there will be first a layer of compressed cotton three feet, two inches in thickness, after the cotton has been compressed. Upon this layer of compressed cotton there is disposed a plate 14 which will be approximately two inches 70 thick, upon this steel plate there will be disposed another layer of cotton about three feet, two inches in thickness and then another steel plate, until the compartment has been entirely filled with compressed cotton and steel plates. Thus, for instance, assuming that each compartment is ten feet deep, 75 there will be three layers of cotton, each 80 three feet, two inches thick and three steel plates, each two inches thick, thus making a filling 10 feet in depth. This mass of cotton with the intervening steel plates are held to the outer wall by threaded bolts 15 extending 85 perpendicularly to the wall, and preferably extending vertically. To each compartment there will preferably be six of these threaded bolts, each six inches in diameter. Each steel plate 14 is to have openings for the passage of the bolts 15 and is to be held in place by nuts 16. The final or last layer of cotton is to be held in place by a cap plate 17, which will be preferably ten 90 feet, four inches square. The reason for 100 making the cap plate larger than the plates 14 is to permit the edge of the steel cap, where it comes in contact with the wall of a ship or with a partition wall 18, to fit into

a groove, say two inches in diameter, this groove being designated 19. The partitions 18 are to be six inches in thickness and ten feet high. Preferably the partitions 18, 5 where they touch the hull, will be provided with flanges whereby the partitions may be riveted or bolted to the outer wall 10. Of course it will be understood that the cotton and the intervening plates 14 and partitions 10 will conform to the curvature of the hull of the vessel and that while I have shown a vessel having a relatively flat bottom, it will be obvious that the construction is equally applicable to vessels having their bottoms at 15 a less angle to the sides.

It is to be understood that while I have referred to the compartments 11 as being ten feet square and ten or more feet deep, these dimensions will be varied depending 20 upon the size of the vessel, the principle of my invention residing in the formation of the hull of a vessel of cells, within which compressed cotton is disposed. Thus these cells or compartments need only, in some 25 cases, be a foot or two feet square and deep. Neither do I wish to limit myself to the particular means of construction illustrated in the drawings or the particular shape of the compartments or cells, nor the particular 30 manner of holding the cotton under compression.

It will be understood that a vessel constructed in accordance with this invention will be practically unsinkable. Being constructed 35 in compartments, the puncture or any damage done to one compartment will not affect the other compartments and, furthermore, the cotton being under compression will quickly swell so as to stop any 40 liquid that may occur due to a puncture in the outer wall of the compartment. Again it will be obvious that a projectile, such as a torpedo, exploding against the side of the vessel will do relatively little damage. The 45 projectile would have great difficulty in penetrating the mass of cotton and an explosion within this mass would have very little effect because of the cushioning action of the cotton and an explosion which would 50 damage a portion of the outer wall of the hull, while it might carry away a portion of this outer wall and carry away a portion of the cotton immediately adjacent, would not affect, to any extent, the inner layers of 55 cotton which would still be held in compression by the jaws in the bolts. The vessel would carry cotton compressed in bales or layers three feet, two inches thick, according to the size of the compartments, which could 60 be readily placed in position, the nuts on the bolts 15 being turned so as to force what were the inner layers of cotton outward so

as to permit the fresh layers to be put in place from the inside.

Having described my invention, what I 65 claim is:—

1. A vessel having a hull formed with a plurality of compartments, bolts extending through the compartments to the open ends thereof, layers of compressed fibrous material disposed within the compartments, metallic plates separating said layers, bolts passing through openings in the plates and in the layers, nuts engaging the bolts and holding the plates in place and the layers 75 of fibrous material under compression, and a cap plate closing the outer end of each compartment and held in place by said bolts.

2. A vessel having an outer wall, many-sided compartments formed upon the outer 80 wall of the vessel on the inside face thereof, each compartment having its walls formed of metallic plates extending perpendicularly to the wall of the vessel and bolted thereto, bolts extending through each compartment 85 and engaging the outer wall of the vessel, layers of compressed cotton disposed within each compartment, metallic plates having an area equal to the cross sectional area of each 90 compartment and disposed between said layers, nuts on the bolts holding each of said plates in place, and a cap plate closing the ends of the compartments and with which said bolts engage, the walls with which the cap plate engages being grooved to receive 95 the edges of the cap plate.

3. A vessel having an outer wall formed to provide the bottom and two sides of the hull of the vessel, many-sided compartments formed upon the inside face of the wall of 100 the hull, each compartment having walls formed of metallic plates extending perpendicularly to the wall of the vessel and bolted thereto, said compartments extending across the bottom of the vessel and the sides of the 105 vessel having compartments extending vertically upward, bolts extending vertically through each compartment and engaging the outer wall of the vessel, layers of compressed cotton disposed within each compartment, a plurality of metallic plates in 110 each compartment and disposed between said layers and through which plates the bolts pass, nuts on the bolts holding the plates in place, and cap plates forming the outer walls 115 of the compartments and with which said bolts engage.

In testimony whereof I hereunto affix my signature in the presence of two witnesses.

TALBERT GRANT WEAVER.
